UNITED STATES PATENT OFFICE

2,454,832

ELECTRIC SERVO

Charles L. Paulus, Dayton, Ohio

Application February 20, 1946, Serial No. 649,107

3 Claims. (Cl. 318—282)

(Granted under the act of March 3, 1883, as
amended April 30, 1928; 370 O. G. 757)

1

The invention described herein may be manufactured and used by or for the Government for governmental purposes without payment to me of any royalty thereon.

This invention relates to electric servos, the embodiment shown being particularly adapted to remotely controlled vehicles such as small radio controlled airplane targets.

An object of the invention is to provide a structure wherein all parts may be assembled on a frame structure and given final inspection and test before the outer casing which shields against dirt and moisture is applied thereto.

Another object is to provide a novel sealing means between the dust cover and the main frame and around the output shaft where it emerges from the main frame.

Another object is to provide an electrical outlet as part of the main frame.

Another object is to provide a centering switch which will automatically stop the power take-off arm in the mid position of its travel.

Another object is to provide a limit switch which will automatically stop the power take-off arm at preselected points in its travel away from its mid position.

Another object is to so position the limit and centering switches and the necessary gearing on the main frame that space is left for the wiring which must necessarily terminate at the electrical outlet.

Another object is to position the motor on the subframe by using the antifriction bearing of the motor as a dowel between the motor and the main frame.

Another object is to provide a mounting for the motor which requires no ears or projections on the motor itself.

Other objects and advantages will appear as the invention is described in greater detail and reference is made to the drawings, wherein;

Fig. 1 is a left-hand end view of an embodiment of my invention showing the power take-off arm, the electrical outlet and the mounting bracket.

Fig. 2 is in part a side view and in part a longitudinal sectional view extending through the cam operated switches, the gearing and the electrical outlet, that part of the view which is taken through the switches and the gearing being taken on the line 2—2 of Fig. 1 and that part which is taken through the electrical outlet being taken on the line 2—2a of Fig. 1.

Fig. 3 is a transverse section through the cam

2

operated limit switch taken at 3—3 of Fig. 2 showing both sides of the switch open.

Fig. 4 is a transverse section through the cam operated centering switch taken at 4—4 of Fig. 2 showing both sides of the switch closed.

Fig. 5 is a transverse section through a part of the speed reducing gearing taken on the line 5—5 of Fig. 2.

Fig. 6 is a transverse section taken at 6—6 of Fig. 2 through the first of the speed reducing gears and the motor pinion which drives it, the motor being shown in dotted lines.

Fig. 7 is a partial longitudinal section taken at 7—7 of Fig. 6 to show the motor mounting.

Fig. 8 is a detail view of the controlled rod mounting.

Fig. 9 is a wiring diagram of the electric circuits.

Figs. 10 through 13 show the same electric circuit as Fig. 9, but in different states of its operation.

Like reference characters refer to like parts throughout the several views.

Referring to the drawings, a main frame 10 which may preferably be produced by die casting or similar means is provided with axially extending bosses 12 to the free ends of which a subframe 14 is secured by screws 16. The subframe 14 is a circular disc which may conveniently be punched from relatively thick sheet metal or it may be otherwise fabricated.

The output shaft 18 of the device has bearing at the forward end in a boss 20 carried on the inside face of the main frame 10 and at the rearward end 22, has bearing in an opening in the subframe 14. A conventional seal 24 is press fitted into a boss 19 on the frame 10 and surrounds the shaft 18 where it emerges from the main housing 10 in order to make a waterproof seal around the oscillating shaft.

The outer end of the output shaft 18 is enlarged and externally serrated as at 26 to correspond to internal serrations in the inside of the hub of the output lever 28. The end of the output lever 28 is split as at 30 so that a screw 32 may clamp the lever 30 on the shaft in a selected position.

In order to protect the mechanism against shock, the lower or power take-off end of the lever 28 (see Fig. 8) is provided with a liner 21 of rubber or other resilient material, and a second liner 23 of metal within the first liner. A stud 25 is fitted to the metal liner 23 and is held in place by the head 27 and a nut 29. A ball end 31 is held in the bottom of a socket 33 by a plug

35 which is pressed against the ball by a spring 37. The spring 37 is held in the socket by a pin 39. The socket 33 is slotted at 41 for the stud 25. A rod 43 conveys the power impulses from the socket 33 to the various controls which the device is designed to operate.

Mounted alongside the hub 20 on the shaft 18 is a collar 34 (see Fig. 2) which is fastened to the shaft 18 by a pin 36. Cut integral on the collar 34 are a centering cam 38 and a limit cam 40. Centering cam 38 (see Fig. 3) operates a centering switch 42 which is insulatedly secured to a lug 44 which is part of the main frame 10. Limit cam 40 (see Fig. 4) operates a limit switch 46 which is insulatedly secured to the lug 44 alongside the centering switch 42.

The centering switch 42 is made up of an upper flexible blade 48, a lower flexible blade 50 and a middle flexible blade 52, the three blades being insulated from each other, from the lug 44, and from the screws 54 which fasten the blades to the lug as shown.

A dielectric rider 56 (see Fig. 3) is carried on the free end of the middle blade 52 and, in the center position shown, rests on a lobe 37 of the cam 38.

When the cam 38 is in the mid position shown, the rider 56, resting on the lobe 37, holds the middle blade 52 out of contact with both the upper blade 48 and the lower blade 50. The middle blade 52, however, is tensioned to spring downward, whereby, when the cam 38 rotates clockwise, the rider 56 will drop to the lower position 39 of the cam whereby the middle blade 52 will engage the lower blade 50, while, if the cam 38 rotates anticlockwise, the rider 56 will be raised, whereby the middle blade 52 will be forced upward away from the lower blade 50 and will engage the upper blade 48.

To facilitate description and identification in the claims, the blades 48, 50, and 52 will hereinafter be referred to respectively as the centering switch first, second, and third contact members. The limit switch 46 comprises an upper flexible blade 58, a lower flexible blade 60 and a middle flexible blade 62, the three blades being insulated from the lug 44 and from the screws 54 which fasten the blades to the lug as shown.

A dielectric rider 64 (see Fig. 4) is carried on the free end of the middle blade 62 and rests on the cam 40. When the cam 40 is in the mid position shown, the rider 64 holds the middle blade 62 in electrical engagement with both the upper blade 58 and the lower blade 60. The middle blade 62 however, is tensioned to spring downward whereby when the cam 40 rotates clockwise, as much as 30° from the central position shown, the rider 64 will drop to the lower lobe 66 of the cam whereby the middle blade 62 will drop away from the upper blade 58, thus severing electrical contact between them, but will continue to engage the lower blade 60. On the other hand, if the cam 40 rotates anticlockwise as much as 30° from the central position shown, the rider 64 will be raised to the upper lobe 68 of the cam, thus separating electrical connections between the middle blade 62 and the lower blade 60 but maintaining electrical connection between the middle blade 62 and the upper blade 58.

For purposes of identification in the claims, the limit switch blades 58, 60, and 62 will hereinafter be referred to respectively as the limit switch first, second, and third contact members.

Secured to the main shaft 18 for rotation therewith is a main drive gear 70 (see Fig. 2) which

may be silver soldered or similarly secured to the shaft. Alongside the main drive gear 70 is a pinion 72 and a gear 74 which are freely rotatable on the main shaft. Pinion 72 and gear 74 may be made integral or be made separately and fastened together to rotate as one.

A countershaft 76 has one end supported in a boss 78 on the main frame 10 and the other end in an opening in the subframe 14. A pinion 80 and gear 82 are in mesh respectively with the gear 70 and pinion 72. Pinion 80 and gear 82 are freely rotatable on the countershaft 76 and may be made integral or fastened together in any suitable manner to rotate as one.

15 A pinion 84 and gear 86 are freely rotatable on the countershaft 76. They may be made integral or may be fastened together to rotate in unison. Pinion 84 is in mesh with the gear 74 while the teeth of the gear 86 are engaged by the teeth of a pinion 88 (see Fig. 6) which is carried on the shaft 90 of an electric motor 92 (see Fig. 7).

The electric motor 92 is secured to the subframe 14 by screws 94. A relay 96 also carried by the subframe 14 is fastened thereto by screws 98. The windings and connections of the motor 92 and the relay 96 will be best understood from the wiring diagram, Fig. 9.

The motor 92 is of the permanent magnet field type and is therefore reversible only by changing 30 the direction of the current through the armature, the relay 96 being provided for this purpose. As may be seen in the wiring diagrams, Figs. 9 through 13, the relay, when no current is passing through its coil, is spring biased to cause the 35 common contacts 129 and 131 to engage the contacts 124 and 126 as seen in Figs. 9, 10, and 13 for producing clockwise movement of the motor and output lever 28, but, when current is directed through its coil, will cause the common contacts 40 129 and 131 to make contact with the lower contacts 128 and 130 as seen in Figs. 11 and 12 for anticlockwise rotation of the motor and lever 28.

For convenience in description and for identification in the claims and without intent to impose 45 any structural limitation, the contacts 124 and 126 will hereinafter be referred to respectively as the relay first and second contact members, and the contacts 128 and 130 will be referred to respectively as the relay third and fourth contact members. The common contacts 129 and 131 will be referred to respectively as the relay fifth and sixth contact members.

The motor terminals 133 and 135 will be referred to respectively as the motor first and second 55 terminals.

A unique manner of positioning the motor on the subframe 14 to insure correct meshing of its pinion 88 with the gear 86 is shown in Fig. 7. Here the ball bearings 108 is allowed to protrude 60 slightly from its seat in the motor and a corresponding counterbore in the subframe 14 is provided to receive the protruding part of the bearing.

The electrical terminal boss 102 (see Fig. 2) is 65 of a standard type and is designed to be waterproof. The contact pins, designated in the wiring diagram as A, B, C, and D are imbedded in dielectric 106 and bring in the current from the outside of the housing to the relay 96 and motor 92 and to the centering and limit switches 42 and 46. The wiring of the motor relay and switches is shown in the diagrams, Figs. 9 through 13.

The bracket 108 (see Fig. 1) by which the unit 75 is mounted on the aircraft or other mechanism which it is to control consists of a metal strip

enlarged at 110 intermediate its ends and having an opening within the enlarged portion which fits over the hub 19 (see Fig. 2). The mounting bracket 108 is fastened to the main frame 10 by screws 112. The free ends of the bracket may be provided with suitable means for securing the bracket to the aircraft.

At the forward end of the main frame 10, an annular groove is provided to receive the seal ring 114. The seal ring is made of rubber or other gasket material and extends outwardly beyond the groove. After the entire device is completely assembled and tested and mounted on the aircraft where it is to be used, a dust cover 116 may be slid over the subframe 14 and frame 10 with the open end of the cover against the projecting portion of the seal ring 114 and the cover drawn up to the ring by screws 116.

The advantage of this housing construction is obvious. The entire unit may be assembled and tested and even put into actual use without the dust cover in place. In this way, the device may be seen in action before the cover is put on.

In the wiring diagram A is the terminal which is permanently connected to the one side of a source of electrical energy. B, C, and D are selectively connectible to the other side for moving the control rod 43 (see Fig. 8) to the left center or right, respectively. Switch means 118, 120, and 122 are provided whereby whenever the said other side is not selectively connected to B or D, it is automatically connected to C which is of the same polarity as B and D. Switches 118 and 122 are schematically shown as being spring biased to the open position, and switch 120 as being spring biased to the closed position. Switches 118 and 122 as shown are manually closable, but it will be understood that they may, within appropriate radio signal receiving means be closable by the sender of radio signals from a distance.

The operation of the servo unit is substantially as follows:

Assuming the device to be in the inactive state as seen in Fig. 9, wherein both sides of the centering switch 42 are open, both sides of the limit switch 46 are closed, and the contacts 129 and 131 of the relay 96 are spring biased to the upper position and therefore closed onto the contacts 124 and 126. The terminal A is shown as permanently connected to the positive side of the current source.

If it is now desired to rotate the output arm clockwise, the terminal B may be selectively connected to the negative side of the power source as by a switch 118 as shown in Fig. 10 whereby current will flow to the relay contacts 126 and 131, through the motor from the contact 135 to the contact 133, to rotate it clockwise, then through the relay contacts 129 and 124, limit switch blade 58 and 62 to the positive power terminal A.

As soon as the motor 92 starts, the centering cam 38 will cause the blade 52 of the centering switch 42 (see Fig. 3) to make electrical contact with the blade 50 as seen in Fig. 10, and this contact will remain in effect as long as the operating arm 28 is turned clockwise off the central or home position shown in Fig. 1. However, when the output shaft 18 becomes turned as much as 30° from the home position, the limit switch cam 40 will cause the blade 62 to be withdrawn out of contact with the blade 58 as seen in Fig. 11 which will break the circuit through the motor 92 causing it to cease rotation.

In order now to return the output lever 28 to the central or home position, the switch 118 of the negative terminal B is merely released whereupon the switch 120 of the negative terminal C automatically engages, and current passes through the blades 52 and 50 of the centering switch 42 and through the coil of the relay 96 which shifts the relay to cause the contacts 129 and 131 to engage the contacts 128 and 130 so that current may pass through contact members 128 and 129 and through the motor from terminal 133 to terminal 135 through terminals 131 and 130 and through limit switch blades 60 and 62 to the positive terminal A which will rotate the motor anticlockwise and return the output lever 28 to the home position.

As soon as the output shaft 18 starts to return from the 30° position, toward the home position, the limit cam 40 will cause the limit switch blade 62 to re-engage the blade 58 and when the home position is reached, the blade 52 of the centering switch 42 is withdrawn from the blade 50 whereby both sides of the centering switch will again be open and both sides of the limit switch will again be closed as in Fig. 9.

When it is desired to rotate the output lever 28, anticlockwise, the terminal D may be selectively connected to the negative side of the power source as by the switch 122 (see Fig. 12) whereby current will first flow to the coil of the relay 96 to close the relay contacts 129 and 131 onto the contacts 128 and 130 whereby current will flow through the motor from the motor terminal 133 to motor terminal 135 for anticlockwise rotation of the motor and the output lever.

As soon as anticlockwise rotation begins, the blade 52 of the centering switch 42 (see Fig. 3) engages the blade 48 as shown in Fig. 12 and this contact will maintain as long as the operating arm 28 is turned anticlockwise off the central or home position seen in Fig. 1. However, when the output shaft 18 becomes turned anticlockwise as much as 30° from the home position, the limit switch blade 62 will be withdrawn out of contact with the blade 60 as seen in Fig. 13, which will break the circuit through the motor 92 causing it to cease rotation, and will break the circuit through the coil of the relay 96 thereby allowing the contacts 124 and 126 to be re-engaged by the contacts 129 and 131.

In order now to return the output lever 28 to the central or home position, the switch 122 of the negative terminal D is released, whereupon, the switch 120 of the negative terminal C automatically engages and the current passes through the blades 52 and 48 of the centering switch 42 to the contacts 126 and 131 through the motor from terminal 135 to terminal 133 for clockwise operation and through the contacts 129 and 124 and terminals 58 and 62 of the limit switch 46 back to positive terminal A whereby the output arm is returned to the home position.

From the foregoing description, it will be seen that closing the switch 118 to negatively energize the terminal B will rock the lever 28 clockwise and opening the switch at any position of the lever 28 will return the lever to the home position, provided, however, that it cannot be rocked clockwise more than 30° from the home position because the limit switch 46 breaks the circuit at that point by separating the contact blades 62 and 58. Moreover, at the beginning of its rocking movement, the centering switch 42 connects its blades 52 and 50 so that when the terminal B is de-energized and the terminal C thereby

automatically energized, the relay will reverse the current in the motor to return the lever to the home position.

It is equally obvious that energizing the terminal D by means of the switch 122 will rock the lever 28 anticlockwise as much as 30°, but no more and will return it from any position to the home position upon de-energization of terminal D and the consequent automatic energization of terminal C.

It will, of course, be understood that while the wiring diagram shows the terminal A as positive and terminals B, C, and D as negative, the arrangement is equally operative if A is negatively energized and B, C, and D are positively energized.

Having described an embodiment of my invention whereby the objects hereinbefore set forth are attained, I claim:

1. In an electric servo unit having a frame, an output shaft having bearings in said frame and adapted to rock in said bearings, an electric motor, said motor having first and second terminals carried by said frame, and a speed reducing gear train connecting said motor to said output shaft, the improved control mechanism which comprises a first power terminal of one polarity, a second, a third and a fourth power terminal of the other polarity, a relay coil, relay first and second contact members, relay third and fourth contact members, relay fifth and sixth contact members, yieldable means biasing said relay fifth and sixth contact members into engagement with said relay first and second contact members respectively, a relay core operative upon energization of said coil to move said relay fifth and sixth contact members into engagement with said relay third and fourth contact members, respectively, centering switch first and second contact members, a centering switch third contact member normally out of electrical contact with the centering switch first and second contact members, a centering switch cam operative when rotated one direction to engage said centering switch third contact member with said centering switch second contact member and operative when rotated in the other direction to engage said centering switch third contact member with said centering switch first contact member, limit switch first and second contact members, a limit switch third contact member normally in electrical contact with the limit switch first and second contact members, a limit switch cam operative when rotated in one direction to disengage the limit switch third contact member from the limit switch first contact member, and operative when rotated in the other direction to disengage the limit switch third contact member from the limit switch second contact member, and electrical conductors connecting said first power terminal to the limit switch third contact member; connecting said second power terminal to the centering switch first contact member and the relay second contact member; connecting said third power terminal to the centering switch third contact member; connecting the said fourth power terminal to the said centering switch second contact member, to one end of said relay coil and to said relay third contact member; connecting the other end of said relay coil to the said relay fourth contact member and to the limit switch

second contact member; connecting the said relay first contact member to the said limit switch first contact member; and connecting the said relay fifth and sixth contact members to the motor first and second terminals, respectively.

- 5 2. In an electric servo power unit, first, second, third and fourth power terminals, fixed means for applying an E. M. F. of one polarity to the first power terminal, selective means for applying an E. M. F. of the other polarity to the second or fourth power terminals, means automatically responsive to release of both said selective means for applying an E. M. F. of said other polarity to said third power terminal, an electric motor, motor first and second terminals, a relay, a relay coil, first, second, third, fourth, fifth, and sixth contacts carried by said relay, a relay core normally operative to yieldably engage the relay fifth and sixth contacts with the relay first and second contacts but operative upon energization to engage the relay fifth and sixth contacts with the relay third and fourth contacts, a centering switch including centering switch first, second, and third contacts, the third contact being normally out of engagement with the first and second contact, a centering cam operative when rotated in one direction to engage said centering switch third contact with said centering switch second contact and operative when rotated in the other direction to engage said centering switch third contact with said centering switch first contact, a limit switch including limit switch first, second, and third contacts, the limit switch third contact being normally in engagement with the limit switch first and second contact, a limit cam operative when rotated in one direction to disengage the limit switch third contact from the limit switch first contact, and operative when rotated in the other direction to disengage the limit switch third contact from the limit switch second contact, and electrical conductors connecting said first power terminal to the limit switch third contact; connecting said second power terminal to the centering switch first contact and the relay second contact; connecting said third power terminal to the centering switch third contact; connecting the said fourth power terminal to the said centering switch second contact, to one end of said relay coil and to said relay third contact; connecting the other end of said relay coil to the said relay fourth contact and to the limit switch second contact; connecting the said relay first contact to the said limit switch first contact; and connecting the said relay fifth and sixth contacts to the motor first and second terminals respectively.
- 10 3. The device of claim 2 wherein the centering and limit switches are on a low speed shaft and a speed reducing gear train connects the motor to the said low speed shaft.
